(57) **CLAIM**

I claim the ornamental design for a medical garment, as shown and described.

DESCRIPTION

FIG. 1 is a perspective view of a medical garment, showing my new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof; and,

FIG. 8 is a perspective view thereof, illustrated inside-out with respect to FIG. 1.

The broken lines showing a medical tube traversing a pocket aperture in FIG. 8 depict environmental matter and form no part of the claimed design.
